UNITED STATES PATENT OFFICE.

WILLIAM E. TOELLE, OF NEW YORK, N. Y.

TOY BOWLING-ALLEY.

1,172,570.

Specification of Letters Patent. Patented Feb. 22, 1916.

Application filed April 23, 1915. Serial No. 23,354.

To all whom it may concern:

Be it known that I, WILLIAM E. TOELLE, a citizen of the United States, and a resident of the borough of Manhattan, in the city, county, and State of New York, have invented a certain new and useful Improvement in Toy Bowling-Alleys, of which improvement the following is a specification.

This invention relates to a miniature toy 10 bowling alley, in which the ball is delivered by an image, preferably in the form of a man, to be manipulated by the players, the principal object being to provide a mechanical figure having a swinging arm and hand adapted to hold and deliver the ball in a manner similar to that practised by the 15 players in a regular bowling game.

Another object is to provide for an adjustment of the position of the figure transversely of the alley in order that skill may 20 be exercised in the placing of the figure in the best position to knock down the pins.

With these and other objects in view, my 25 invention comprises the particular combinations hereinafter more fully described and set forth in the appended claims.

In the accompanying drawing: Figure 1 is a side elevation of a toy bowling alley 30 and an image embodying my improvement; Fig. 2, a plan of the alley and transversely sliding base plate with the image removed; and Fig. 3, a front elevation of the image with certain parts broken away in order to more fully show the mechanism.

As shown in the drawing, the alley board, 5, may be formed in the usual manner, of wood or other suitable material, having gutters, 6, and a place for setting up the pins, 7, at one end. At the other end is located 40 the base plate, 8, mounted to slide transversely of the alley and having a portion, 9, engaging a transverse groove, 10, in the alley board. This connection is designed to have sufficient frictional resistance to retain 45 the base plate in any position to which it may be adjusted. On the base plate is mounted a toy figure representing the image of a man, 11, having an arm, 12, and hand, 13, for holding the ball, 14. In bowling, 50 players usually hold the ball by inserting the thumb and one finger, usually the second, in holes formed in the ball for this purpose, and the hand of the image is designed to hold the ball in the same way, the thumb, 15, being inserted in one hole, 55 and the finger, 16, in the other hole in the

ball. In order that these members may have a sufficient grip upon the ball to hold it during the swinging movement of the arm, one of the members, such as the finger, 16, is movable, being pivotally mounted on the bell crank, 17, having a spring, 18, normally clamping said finger against the ball. For releasing this finger, a pin, 19, is carried by the hand, and is adapted to engage 60 a fixed projection, 20, at the forward position of the arm, as indicated in dotted lines in Fig. 1.

The arm, 12, is mounted to swing at the shoulder, being supported on the end of a 70 shaft, 21, having bearings fixed in the body of the figure, and provided with a crank arm, 22, and a spring, 23, normally tending to swing the arm forward. A trigger mechanism, such as pivoted arm, 24, with spring, 25, and push rod, 26, is provided for holding the arm, 12, in its retracted position and releasing same when desired. The rod, 26, may be connected to the head, 27, of the 75 image, and a notch, 28, may be formed in the arm, 12, to permit the same to swing past the trip, 24, when the latter is pushed down to its lower position.

After the pins, 7, have been properly 80 placed upon the board, the image is operated by first placing the ball upon the hand, inserting the thumb and finger into the holes in the ball, and then swinging the arm back to its retracted position in which the spring, 23, is stretched and the trip, 24, 85 projects in front of the arm, 12, retaining it in this position. The player then slides the image along the transverse groove, 10, to what he regards as the most advantageous 90 position for knocking down the pins, and then depresses the head and the trip lever, 24, to release the arm, 12. The spring, 23, then swings the arm forward with considerable force, and when the pin, 19, strikes the fixed stop, 20, the finger, 16, is moved, 95 and the ball being released, is delivered 100 upon the alley.

It will now be seen that I have provided a simple construction in which the movement in delivering the ball is similar to that 105 in the regular game of bowling, and that the position of the image may be adjusted transversely of the alley as desired.

Having now described my invention, what I claim as new and desire to secure by Letters Patent is:

1. In a ball projecting toy, the combina-

tion of an image having a movable arm and hand provided with projecting fingers adapted to extend into holes in a ball for holding the same, and means for swinging 5 said arm to deliver the ball.

2. In a ball projecting toy, the combination of an image having a movable arm, a hand on said arm and provided with a projecting finger adapted to extend into a hole 10 in a ball, and means for swinging said arm to deliver the ball.

3. In a ball projecting toy, the combination of an image having a movable arm, a hand on said arm and provided with projecting fingers adapted to extend into holes 15 in a ball for holding the same, one of said fingers being movable, means for swinging the arm, and a device for tripping said movable finger during the forward movement 20 of the arm.

4. In a ball projecting toy, the combina-

tion of an image having a movable arm, a hand on said arm and provided with projecting fingers adapted to extend into holes 25 in a ball for holding the same, one of said fingers being movable, a spring acting on said movable finger, another spring for swinging the arm forward, and a tripping device for releasing said movable finger at the forward movement of the arm. 30

5. In a ball projecting toy, the combination of an image having a movable arm for delivering a ball, a spring for swinging said arm forward, a trigger mechanism mounted on the image for holding said arm in a retracted position, and a movable member on the image for releasing said trigger mechanism. 35
